UNITED STATES PATENT OFFICE.

FRANK C. MARQUARDT, OF NEW YORK, N. Y., ASSIGNOR TO AMERICAN BANK NOTE COMPANY, A CORPORATION OF NEW YORK.

PRINTING-MACHINE.

1,132,481.

specification of Letters Patent. Patented Mar. 16, 1915.

Application filed July 5, 1913. Serial No. 777,395.

To all whom it may concern:

Be it known that I, FRANK C. MARQUARDT, a citizen of the United States, residing at the borough of Brooklyn, in the city of New York, county of Kings, and State of New York, have invented certain new and useful Improvements in Printing-Machines, of which the following is a specification, reference being had therein to the accompanying drawings, which form a part thereof.

My invention relates to printing machines, and more particularly to a type of rotary plate printing machine.

The main object of the invention is to provide a rotary plate printing machine wherein the impression cylinder or D-roll will be rotated in a manner to permit the machine to be run at high speeds.

A further object is to provide controlling means for said impression cylinder or D-roll whereby it will be brought to a positive stop between impressions and held in the same position preparatory to each impression, whereby upon receiving its initial or starting impulse, it will be thrown into frictional engagement with the printing plate in such relation thereto as to bring the same portion of the blanket into engagement with the printing portion of the plate or plates with each impression.

A still further object is to provide means whereby the peripheral velocity of the impression cylinder or D-roll will be synchronized with that of the plate cylinder through compensating means adapted to permit the actuating means for the impression cylinder or D-roll to adapt itself to the velocity of said cylinder or D-roll in case of a loss of uniformity in such peripheral velocities due to a variance in the thickness of different blankets or plates, temperature conditions or other causes resulting in variances in the relative diameter of the impression cylinder or D-roll, and the plate cylinder when made ready for a run of the machine.

A still further object is to provide means whereby the machine may be adjusted to time to a nicety, the initial impulse imparted to the impression cylinder or D-roll.

A still further object is to provide means adapted to mechanically and momentarily

check the rotation of the impression cylinder or D-roll after the completion of each rotation thereof.

A still further object is to provide the actuating means for the impression cylinder or D-roll with a removable, adjustable member adapted to arrest rotary movement of the said cylinder or D-roll to insure its proper positioning and permit the adjustment of, or repairs to, the machine, by the resetting or replacing of this member.

A still further object is to provide means whereby the actuating member of the impression cylinder or D-roll may be thrown into or out of the operative relation to the coöperating means carried by the plate cylinder without disturbing the proper position of said cylinder or D-roll relative to said plate cylinder.

A still further object is to provide means whereby movement of said D-roll actuating means is prevented excepting when said plate cylinder is just coming to or has just passed its printing position. And a still further object is to provide a high speed rotary plate printing machine the design of which will be such as to insure the automatic adjustment of the various parts in a manner to secure reliability in their operation and minimize likelihood of a loss of adjustment in the various coöperating parts.

The invention consists primarily in a printing machine embodying therein a rotary plate cylinder, a rotary impression cylinder, or D-roll, means actuated from said plate cylinder and adapted throughout a portion of the rotation thereof to actuate said impression cylinder or D-roll, coöperating means acting upon said impression cylinder or D-roll, said means and said coöperating means being provided with coöperating portions adapted to arrest the rotary movement of said impression cylinder after each rotation thereof and hold it preparatory to a succeeding rotation, and coöperating members carried by said means and said coöperating means whereby an initial impulse is imparted to said coöperating means to bring them into the operative relation to said means; and in such other novel features of construction and con-

nation of parts as are hereinafter set forth and described, and more particularly pointed out in the claims hereto appended.

Referring to the drawings:—Figure 1 is 5 a fragmentary view of the printing portion of a rotary plate printing machine embodying my invention; Fig. 2 is a side view thereof; Fig. 3 is a similar view on a smaller scale, showing the D-roll actuating mechanism immediately after receiving its initial impulse; Fig. 4 is a similar view showing the relation of parts when the peripheral speed of the gear driving the D-roll exceeds that of the gear meshing therewith; Fig. 5 10 is a diagrammatic view of the printing and appurtenant mechanisms of a machine embodying my invention; and Fig. 6 is a detail view of the interlocking device of the main controlling mechanism.

20 Like numerals refer to like parts throughout the several views.

In rotary printing presses for using engraved, intaglio or undersurface plates, it is necessary to have the impression cylinder 25 driven at the same peripheral speed as the plates, and to have the pressure between this cylinder and the plate or plates much greater than is required in the ordinary surface printing press in order to cause the resilient surface of the cylinder to be forced 30 within the lines of the plate to insure the taking up by the paper of a sufficient quantity of ink to secure a good, clean impression. The blanket of the impression cylinder 35 should be drawn taut to avoid such wrinkling as would result in imperfect imprints. By reason of these conditions, the impression cylinder usually employed has a portion of its periphery cut away, the 40 holding and tightening means engaging the ends of the blanket being located in this cutaway portion. An impression cylinder of this character is known as a D-roll.

The D-roll, excepting when an impression is being taken, remains stationary, means being provided to bring the roll into engagement with the plate at a predetermined point to insure the engagement of the same portions of the impression surface 45 with the same portions of the plate or plates upon each actuation thereof in order to cause the cameo offset which forms upon the impression surface to come into register with the corresponding intaglio lines 50 of the plate with each impression. This offset is a mere "ferming" of the impression surface, no ink being transferred to the D-roll. It is necessary to provide means for arresting the rotary movement of the 55 D-roll after each impression in order to prevent the gradual creeping of the roll, which would result in a loss of register between the offset upon the impression surface and the plates, as well as to insure the proper

relative position of the actuating means for 65 the D-roll and the coöperating means upon the cylinder.

By my present invention, I provide a construction whereby the impression cylinder is positively brought to rest after each impression, and in a definite position which will insure the proper relation of parts at all times, the means for holding the D-roll stationary becoming inoperative simultaneously with the imparting to the D-roll of 70 the initial impulse for bringing it into engagement with the plate, and the actuating means therefor into register with the coöperating means upon the impression cylinder. In connection with this construction, I provide means whereby the D-roll is permitted to creep slightly while the impression is being made, thus permitting the D-roll to be driven to all intents and purposes by frictional engagement with the 75 plate, and driving means for assisting this frictional drive so as to avoid any possibility of slippage, at the same time affording sufficient flexibility in the drive to permit a slight fluctuation in the peripheral 80 speed of the D-roll independently of said driving means. This means, as will more fully appear hereinafter, will permit a mechanical driving of the D-roll, and compensate for any such fluctuations as are 85 above referred to by means becoming operative at the end of each impression to check further rotation of the D-roll after the mechanical drive becomes inoperative 90 in relation thereto.

In the accompanying drawings, I have shown a positively driven main shaft 1, the said shaft having mounted thereon and rotatable therewith the plate or form cylinder 2, and the main gear 3. Mounted upon the shaft 4, counter to the shaft 1, is the impression cylinder or D-roll 5, the flattened portion of which is indicated at 6.

In the form of the invention illustrated, the cylinder 2 is adapted to carry two 105 plates, the D-roll making two rotations to one full rotation of said plate cylinder. One plate upon said cylinder 2 is indicated at 7.

The plate cylinder 2 is rotated continuously, the impression cylinder or D-roll being driven intermittently, coming to rest after each impression and receiving a starting impulse from the actuating mechanism for the plate cylinder in a manner to throw 110 said impression cylinder or D-roll into the operative relation to each plate upon said plate cylinder and the coöperating actuating parts controlling said D-roll from said plate cylinder into the operative relation. 115 To secure this mode of operation, I provide the shaft 1 with means adapted through a portion or portions of each rotation of said

shaft to actuate the impression cylinder or D-roll 5, the shaft 4 being provided with means adapted to coöperate therewith, and exert a continuing action upon the D-roll 5 from the impression cylinder to insure the imparting of a continued, approximately uniform peripheral velocity thereto from said plate cylinder. This means comprises a segmental or intermittent gear carried by 10 the shaft 1, the shaft 4 for the D-roll being provided with a coöperating segmental gear adapted to mesh with the gear segments carried by said shaft 1.

To insure the timely engagement and disengagement of the plate cylinder and the D-roll gears, I provide a member carried by said impression cylinder gear, and a co-operating member carried by said D-roll gear, for imparting an initial impulse to 15 the latter and to insure the gears coming to mesh with each other. Intermediate the toothed sections of the plate cylinder gear, I provide means adapted to be engaged by coöperating means on the D-roll gear to 20 arrest or check the rotary movement of said D-roll and hold it in a fixed position between impressions, a construction which results in a unidirectional operation of the D-roll, and causes said D-roll to come to position for a succeeding actuation immediately upon the completion of each rotation thereof.

In the accompanying drawings, the D-roll controlling means carried by the shaft 1 35 comprises a guide adapted to conform to a shoe carried by the D-roll, said guide preferably being made in two sections, 8 and 9, adjustably mounted upon the gear 3 and provided with inwardly presented flanges 10 and 11 adapted to form seats for the segmental rack sections 12 and 13 which are held in position by means of flanges 14 and 15 adapted to project below the rim of said gear 3. Intermediate the racks 12 and 13 40 are the fixed segmental guides 16, 17, 18 and 19, which are of a height corresponding with the diameter of the guides 8 and 9, the sections 16 to 19 being removable for the purpose of facilitating the substitution of 45 parts to compensate for wear at this point. The racks 12 and 13 are identical, being of a sufficient length to impart one operative rotation to the D-roll. This construction is essential because these guides 16 to 19 are 50 provided for the purpose of permitting a dwell of the D-roll between impressions, and for holding said D-roll against rotation in a fixed position, so that it will start under exactly the same conditions with each 55 operative rotation thereof. The shaft 4 of the D-roll has mounted thereon a segmental gear 20, that portion of which corresponding with the cutaway portion of the D-roll proper, 5, is removed, a segmental shoe 21

being inserted in this cut away portion so 65 as to act similarly to a Geneva gear in controlling the operation of said D-roll. To permit nicety in the fitting of the shoe 21, with relation to the guides 16 to 19, I provide the shank of said shoe with slots 22, 70 by means of which this shoe may be adjusted radially of the gear 20 and set in its adjusted position, said gear being recessed to form a socket for said shank.

Carried by each section 8 and 9 of the 75 guide disk is an impact stud 23 or 24, each of which studs is adapted to engage an arm 25 carried by the gear 20, the function of said stud and said arm being to impart an initial impulse to the D-roll, and bring 80 the gear 20 thereof into mesh with either rack 12 or 13 for the purpose of facilitating the further rotation of said D-roll by said racks.

As I have heretofore stated, the peripheral velocity of the D-roll is subject to fluctuations, which preclude a solely mechanical drive thereof; and to permit such fluctuations while insuring the D-roll coming to rest and starting from a predetermined 90 point, I slidably mount the racks 12 and 13 upon the flanges 10 and 11, and provide the springs 26, 27, acting on said racks respectively, which springs are adapted to restore said racks to normal after any displacement 95 thereof, while at the same time permitting slight circumferential movement of said rack sufficient to compensate for any such fluctuations.

The manner of assembling the slidable or 100 floating racks, 12 and 13, between the gear 3 and the guides 8 and 9, having a continuous surface corresponding in diameter with the said rack, prevents displacement of these guides while permitting them to have free 105 movement under the control of the D-roll.

The sections 8 and 9 of the guide disk are made independently adjustable in order to secure a firm support for the impact studs 23 and 24, while at the same time permitting 110 either of these studs to be adjusted slightly circumferentially of the gear 3, at any time and independently of the other, to secure accuracy and nicety in the timing of the initial impulse imparted to the D-roll. 115,

In addition to confining and guiding the racks 12 and 13, the guide disk formed of the sections 8 and 9 serves as a bearing for the shoe 21 when it is desired to throw the D-roll into a position where it will remain inoperative, notwithstanding a continued rotation of the plate cylinder 2, as in starting the device the press is frequently turned over a number of times before paper is fed thereto, and during the run of a press 120 there are frequent stoppages during which it is desirable to make the D-roll inoperative to avoid offsetting of the ink thereon. 125

To permit this throwing of the D-roll into and out of the operative relation to the plate cylinder, the D-roll shaft is provided with means mounted so as to be slidable laterally 5 of the machine, carrying with it its gear 20 and arm 25. Acting upon a collar carried by the shaft 4 is an oscillatory lever 28, one end of which is acted upon by a rack bar 29, controlled by the toothed wheel 30, thus securing 10 sufficient power to insure a quick lateral shifting of the D-roll and its appurtenances. To insure a sufficient movement of the gear 20 and arm 25, and avoid any possibility of their being shifted while the D-roll is in the operative relation to the plates upon the cylinder 2, I provide interlocking means between said means and said plate cylinder, positively preventing a movement of the gear 20 while the D-roll is in engagement 15 with the plates, and at the same time insuring the proper quantity of movement of said gear in throwing it into or out of the operative relation. This interlocking means comprises a cam plate 31, carried by the shaft 1 and having thereon one or more segmental extensions or risers 32, of the same degree as the largest plate which may be mounted on said cylinder 2, the number of such extensions or risers corresponding 20 with the number of plates which may be carried by said cylinder. In the accompanying drawings, I have shown two such extensions or risers.

Each such extension or riser upon the forward edge thereof (with relation to the direction of rotation of the shaft 1) is beveled upon both sides thereof to present a narrow, or knife, edge, 33. Coöoperating with the extensions or risers 32 is an oscillatory lever 34, one arm of which, as 35, is adapted to engage the collar upon the shaft 4, upon which the controlling lever 28 acts, the other arm of said lever, adjacent said cam, being provided with a double faced 40 contact cam 36, approximately diamond shaped, with the acute angular portions thereof, parallel with the extensions or risers 32.

It will thus be seen that when either plate 50 7 is adjacent the D-roll, the contact 36 will be upon one side or the other of the extensions or risers 32, and that these risers will prevent oscillatory movement of the lever 34 until the plate has passed from its position adjacent to the D-roll.

In case the lever 31 shall not have been so moved as to bring the contact 36 upon one side or the other of said extension or risers, the inclined sides of the latter coöoperating 60 with those of the former will shift the lever 34 laterally so as to establish the relation of parts above referred to.

In connection with the foregoing mechanism, I employ an ordinary wiping and pol-

ishing mechanism indicated conventionally 65 in Fig. 6 of the drawings by the reference numerals 37 and 38, and an inking mechanism, shown conventionally in said figure at 39.

Any desired form of feeding and delivery 70 mechanism may be employed in connection with my invention, and as such are well known to those skilled in the art, I have not illustrated any such mechanism in connection with my invention. 75

The operation of the herein described printing machine is substantially as follows:—In starting the press, it is ordinarily desirable to turn the plate cylinder 2 over a number of times before feeding paper to 80 the press, in order to secure a proper conditioning of the wiping and polishing mechanism and of the plates. Under such conditions, the lever 29 is actuated to impart movement to the link 28 to shift the gear 20 to the left in Fig. 1, and move the gear 20 and its shoe 21 so as to cause the latter to engage the periphery of the guides 8 and 9, these guides, together with the racks 12 and 13, and guides 16 to 19 inclusive, intermediate said racks, rotating continuously with the shaft 1 and its plate cylinder 2. When said gear 20 is so shifted, the shoe 21 will bear continuously upon said guides and no movement will be imparted to the D-roll inasmuch as this lateral shifting thereof will 85 position the arm 25 without the operative range of the impact studs 23 and 24. Hence the flattened portion of the D-roll, see Fig. 6, will be presented toward the plates, and 90 these plates will pass below and out of contact with the D-roll. 95

When it is desired to make an impression, the gear 20 is shifted to the right, see Fig. 1, the interlocking means acting 100 to permit the shifting of this gear at a time when no plate is adjacent to said D-roll. This shifting of the gear 20 will bring the shoe 21 to bear upon the guides 16 and 17, as shown in Fig. 2 of the drawings, and position the arm 25 within the path of the stud 23. As the gear 20 is shifted, the lever 34 will be oscillated to bring the contact 36 to the left of the extension or riser 32 upon the cam plate 31, see Fig. 1. 110

With the continued rotation of the plate cylinder, the stud 23 will impact upon the arm 25 when the rear end of the shoe 21 is about to leave the guide 17, thus throwing the gear 20 into mesh with the floating rack 120 12, as shown in Fig. 3, imparting an initial impulse to the D-roll. Immediately prior to the engagement of the stud 23 with the arm 25, the contact 36 will have come into the operative relation to one of the extensions 125 32 upon the cam plate 31, and if the gear 20 has not been thrown to the full extent, the inclined sides of said contact 36

engaging with the extension or riser 32 will impart sufficient oscillatory movement to the lever 34 to complete the throwing of the gear 20. If, by chance, the gear 20 should stop midway of its full lateral movement, the point of the diamond wedge or contact 36 would contact with the narrow or knife edge 33 of the extension or riser 32, and, there being no surfaces to abut against each other, the lever 34 will be thrown either one way or the other to complete the lateral movement of said gear 20, thus preventing the shoe 21 from bearing partly upon the guide 16 or 17, 18 or 19, and the continuous guide 8-9.

By the operation above referred to, blocking of the movement of the gear 20 by the guides 8 and 9 is prevented. In addition to the foregoing function, the interlocking means will prevent any lateral movement of the gear 20 while it is engaged with a plate by reason of the circumferential elongation of each extension or riser 32, this riser or extension blocking oscillatory movement of the lever 34 and a resultant oscillatory movement of the gear 20 during a period co-extensive with the interval during which the D-roll is in contact with a plate.

The gear 20 is thrown into mesh with the rack 12 substantially simultaneously with the engagement of the blanket of the D-roll with the plate or with the plate and the sheet of paper upon which the imprint is being made, and theoretically, the rack 12 will thereafter drive said D-roll at the same peripheral velocity as the plate itself. In practice, however, it is found that it is practically impossible to so nicely adjust the relative diameters of the plate cylinder and its plates, and the D-roll, as to permit an exact mechanical drive which will avoid slippage between the plates and the D-roll. To overcome this structural difficulty, the racks 12 and 13 are permitted to have movement against spring pressure so as to permit that slight fluctuation in the peripheral velocity of the plate cylinder and of the D-roll which occurs at all times during the running of the press.

The tendency of the D-roll is to exceed the peripheral speed of the plate cylinder, and assuming that such a condition exists in the machine shown in the accompanying drawings, after the engagement of the D-roll with the plate, the D-roll will receive from the rack 12 a constant, positive rotary impulse, except when the speed of the D-roll is slightly in excess of that of the plate. Under such conditions, the rack 20 of the D-roll will impart slight movement to the rack 12, against its springs, as shown in Fig. 4, thus compensating for this loss of synchronism in the peripheral speeds of the gear mechanism connecting the impres-

sion cylinder and the D-roll, while permitting the plates upon said plate cylinder and the D-roll itself to rotate at the same peripheral speed. If this fluctuation be but momentarily, the rack 12, will have a return movement to compensate for a slowing down of the gear 20. These fluctuations are very slight, but were not means provided to rectify this error, the sum of such fluctuations in a long run of the machine would cause the D-roll to lose its proper relation to the other co-operating parts of the machine and prevent it from starting each rotation from exactly the same position. This would result in a loss in the register of the cameo offset upon the blanket of the D-roll and the intaglio lines of the plates, thus resulting in inferiority in the quality of the work secured from the press.

Immediately that the D-roll passes from its frictional engagement with a plate, the rack 12, through its spring, will restore the gear 20 to the position relative to the actuating means therefor, carried by the plate cylinder, which it would have had, had there been no speed fluctuations of the D-roll. As the gear 20 passes out of mesh with the rack 12, the shoe 21 will come to a seat upon the guides 18 and 19, and the arm 25 will come to a position where it is adapted to be immediately engaged by the stud 24. The seating of the shoe 21 upon the guides 18 and 19 will momentarily check the rotary movement of the D-roll and prevent any overrunning thereof, holding said D-roll stationary with the flattened portion thereof presented toward the plate cylinder, until the stud 24 impacts with the arm 25, whereupon the D-roll is thrown into mesh with the rack 13 and the operation above described repeated in relation to this rack, the D-roll coming to rest and being held in this position, after disengagement from the rack 13, by the guides 16 and 17.

It will be observed from the foregoing, that the D-roll during a run of the press receives intermittent unidirectional rotation with a momentary dwell between said rotations, sufficient to accurately position the D-roll; and that with each rotation of the said D-roll, the starting and stopping conditions are identical, thus insuring each imprint being made under identical conditions.

In using two or more plates upon the machine, the thickness of these plates may vary slightly without interference with the operation of the press in any way, and slight variations in the thickness of the blankets, through stretching or otherwise, will not interfere with the quality of the work produced. By reason of these conditions, the speed of the press may be materially increased, which fact, together with the reduction in the dwell between actuations of

the D-roll, will appreciably increase the capacity of the machine.

The guides 8 and 9, form a continuous bearing upon which, to establish an inoperative position of it and the plate cylinder, the shoe 21 is adapted to seat when the gear 20 is shifted laterally, the circumferential adjustment of the sections 8 and 9 of said guide being solely for the purpose of permitting that slight adjustment thereof necessary to insure nicely in the timing of the initial impulse imparted by the studs 23 and 24, through the arm 25, to the D-roll.

By using the racks 12 and 13, plates of different dimensions may be used upon the machine; or when a plate cylinder is designed for receiving a plurality of plates, a lesser number than the full capacity of the plate cylinder may be mounted thereon without interfering with the operation of the machine in any way.

The removability of the stop guides 16 to 19 and the removability and adjustability of the shoe 21 are for the purpose of permitting the substitution of parts in case of, and for compensating for, wear upon these parts, these portions of the actuating mechanism being subject to the greatest wear. Furthermore, accuracy in the adjustment of these parts is necessary to insure exactness in the positioning of the D-roll after each rotation thereof.

Various alterations in the design of the structure herein described, and various adaptations of my invention to plate printing presses of different types may be made without departing from the spirit and scope of my invention; and therefore it is not my intention to limit myself to the precise details of construction shown in the accompanying drawings.

Having described my invention, what I claim as new and desire to have protected by Letters Patent, is:—

- 45 1. A printing machine embodying therein a rotary plate cylinder, a rotary impression cylinder or D-roll and means whereby said impression cylinder or D-roll is alternately rotated and held stationary comprising a segmental gear movable with said plate cylinder, a guide terminating adjacent each end thereof, a segmental gear movable with said impression cylinder or D-roll, an elongated surface adjacent the ends of said gear adapted to coöperate with said guide, and coöoperating means movable with said plate cylinder and with said impression cylinder or D-roll respectively whereby an initial or starting impulse is given to said impression cylinder or D-roll to bring said gears into mesh.
- 50 2. A printing machine embodying therein a movable support for a plate, an impression cylinder or D-roll rotatable about a fixed
- 55 axis, means carried by said support for imparting a starting impulse to said impression cylinder or D-roll and throwing it into frictional engagement with the plate on said support, coöperating members carried by said support and said impression cylinder or D-roll, respectively, one of said members being capable of movement by the other to permit fluctuation in the peripheral speed of said impression cylinder or D-roll, a guide adjacent the end of the member carried by said support and a coöperating member carried by said impression cylinder or D-roll adapted to operatively engage said guide whereby rotation of said impression cylinder or D-roll is checked after each rotation thereof and is held in a fixed position until the succeeding actuation of said means for imparting starting impulse thereto.

3. A printing machine embodying therein a movable support for a plate, a rotary impression cylinder or D-roll, means carried by said support for imparting a starting impulse to said impression cylinder or D-roll and throwing it into frictional engagement with the plate on said support, a rack movably supported by said support, a guide adjacent to the end of said rack, a segmental gear carried by said impression cylinder or D-roll adapted to mesh with said first named rack, whereby said D-roll is adapted to move at a peripheral speed at variance with the speed of said rack carried by said support, and a shoe carried by said segmental gear adapted through engagement with said guide to arrest rotary movement of said impression cylinder or D-roll and position it preparatory to a succeeding rotation thereof.

4. A printing machine embodying therein a movable support for a plate, a rotary impression cylinder or D-roll, means carried by said support for imparting a starting impulse to said impression cylinder or D-roll and throwing it into frictional engagement with the plate on said support, coöperating members carried by said support and said impression cylinder or D-roll, respectively, one of said members being capable of movement by the other to permit fluctuation in the peripheral speed of said impression cylinder or D-roll, means adjacent the end of the member carried by said support whereby rotation of said impression cylinder or D-roll is checked after each rotation thereof, and controlling means whereby said first named means and said coöperating members may be made inoperative to prevent the actuation of said impression cylinder or D-roll.

5. A printing machine embodying therein a movable support for a plate, a rotary impression cylinder or D-roll, means carried by said support for imparting a starting impulse to said impression cylinder or D-

65 6. A printing machine embodying therein a movable support for a plate, a rotary impression cylinder or D-roll, means carried by said support for imparting a starting impulse to said impression cylinder or D-roll and throwing it into frictional engagement with the plate on said support, coöperating members carried by said support and said impression cylinder or D-roll, respectively, one of said members being capable of movement by the other to permit fluctuation in the peripheral speed of said impression cylinder or D-roll, a guide adjacent the end of the member carried by said support and a coöperating member carried by said impression cylinder or D-roll adapted to operatively engage said guide whereby rotation of said impression cylinder or D-roll is checked after each rotation thereof and is held in a fixed position until the succeeding actuation of said means for imparting starting impulse thereto.

70 7. A printing machine embodying therein a movable support for a plate, a rotary impression cylinder or D-roll, means carried by said support for imparting a starting impulse to said impression cylinder or D-roll and throwing it into frictional engagement with the plate on said support, a rack movably supported by said support, a guide adjacent to the end of said rack, a segmental gear carried by said impression cylinder or D-roll adapted to mesh with said first named

75 rack, whereby said D-roll is adapted to move at a peripheral speed at variance with the speed of said rack carried by said support, and a shoe carried by said segmental gear adapted through engagement with said guide to arrest rotary movement of said impression cylinder or D-roll and position it

80 preparatory to a succeeding rotation thereof.

85 8. A printing machine embodying therein a movable support for a plate, a rotary impression cylinder or D-roll, means carried by said support for imparting a starting impulse to said impression cylinder or D-roll and throwing it into frictional engagement with the plate on said support, a rack movably supported by said support, a guide adjacent to the end of said rack, a segmental gear carried by said impression cylinder or D-roll adapted to mesh with said first named

90 rack, whereby said D-roll is adapted to move at a peripheral speed at variance with the speed of said rack carried by said support, and a shoe carried by said segmental gear adapted through engagement with said guide to arrest rotary movement of said impression cylinder or D-roll and position it

95 preparatory to a succeeding rotation thereof.

9. A printing machine embodying therein a movable support for a plate, a rotary impression cylinder or D-roll, means carried by said support for imparting a starting impulse to said impression cylinder or D-roll and throwing it into frictional engagement with the plate on said support, a rack movably supported by said support, a guide adjacent to the end of said rack, a segmental gear carried by said impression cylinder or D-roll adapted to mesh with said first named

100 rack, whereby said D-roll is adapted to move at a peripheral speed at variance with the speed of said rack carried by said support, and a shoe carried by said segmental gear adapted through engagement with said guide to arrest rotary movement of said impression cylinder or D-roll and position it

105 preparatory to a succeeding rotation thereof.

10. A printing machine embodying therein a movable support for a plate, a rotary impression cylinder or D-roll, means carried by said support for imparting a starting impulse to said impression cylinder or D-roll and throwing it into frictional engagement with the plate on said support, a rack movably supported by said support, a guide adjacent to the end of said rack, a segmental gear carried by said impression cylinder or D-roll adapted to mesh with said first named

110 rack, whereby said D-roll is adapted to move at a peripheral speed at variance with the speed of said rack carried by said support, and a shoe carried by said segmental gear adapted through engagement with said guide to arrest rotary movement of said impression cylinder or D-roll and position it

115 preparatory to a succeeding rotation thereof.

11. A printing machine embodying therein a movable support for a plate, a rotary impression cylinder or D-roll, means carried by said support for imparting a starting impulse to said impression cylinder or D-roll and throwing it into frictional engagement with the plate on said support, a rack movably supported by said support, a guide adjacent to the end of said rack, a segmental gear carried by said impression cylinder or D-roll adapted to mesh with said first named

120 rack, whereby said D-roll is adapted to move at a peripheral speed at variance with the speed of said rack carried by said support, and a shoe carried by said segmental gear adapted through engagement with said guide to arrest rotary movement of said impression cylinder or D-roll and position it

125 preparatory to a succeeding rotation thereof.

roll and throwing it into frictional engagement with the plate on said support, co-operating members carried by said support and said impression cylinder or D-roll, respectively, one of said members being capable of movement by the other to permit fluctuation in the peripheral speed of said impression cylinder or D-roll, means adjacent the end of the member carried by 5 said support whereby rotation of said impression cylinder or D-roll is checked after each rotation thereof, controlling means whereby said first named means and said co-operating members may be made inoperative 10 to prevent the actuation of said impression cylinder or D-roll, and means preventing the actuation of said last named means while said impression cylinder or D-roll is in frictional engagement with a 15 plate on said support.

6. A printing machine embodying therein a movable support for a plate, a rotary impression cylinder or D-roll, means carried by said support for imparting a starting 20 impulse to said impression cylinder or D-roll and throwing it into frictional engagement with the plate on said support, co-operating members carried by said support and said impression cylinder or D-roll, respectively, one of said members being capable 25 of movement by the other to permit fluctuation in the peripheral speed of said impression cylinder or D-roll, means adjacent the end of the member carried by said support whereby rotation of said impression cylinder or D-roll is checked after each rotation 30 thereof, controlling means whereby said first named means and said co-operating members may be made inoperative to prevent the actuation of said impression cylinder or D-roll, and means preventing the actuation of said last named means while said impression cylinder or D-roll is in frictional engagement with a plate on said support, including therein co-operating members 35 adapted to mechanically complete the actuation of said controlling means to prevent said means being set in a neutral position.

7. A printing machine embodying therein a continuously driven, rotary plate cylinder, a rotary impression cylinder or D-roll, means carried by said plate cylinder and adapted to impart a starting impulse to said impression cylinder or D-roll, and co-operating 40 members carried by said plate cylinder and said impression cylinder or D-roll, consisting of segmental racks and alternate elongated bearing surfaces whereby an intermittent, unidirectional rotary movement 45 is imparted to said impression cylinder or D-roll, and said impression cylinder or D-roll is brought to rest after each rotation thereof.

8. A printing machine embodying therein

a continuously driven, rotary plate cylinder, 65 a rotary impression cylinder or D-roll, means carried by said plate cylinder and adapted to impart a starting impulse to said impression cylinder or D-roll, co-operating members carried by said plate cylinder and 70 said impression cylinder or D-roll, consisting of segmental racks and alternate elongated bearing surfaces whereby an intermittent unidirectional rotary movement is imparted to said impression cylinder or D-roll, and 75 said impression cylinder or D-roll is brought to rest after each rotation thereof, and means whereby one of said members may be moved by the other to permit fluctuations in the peripheral speed of said impression 80 cylinder or D-roll.

9. A printing machine embodying therein a continuously driven, rotary plate cylinder, a rotary impression cylinder or D-roll, means carried by said plate cylinder and 85 adapted to impart a starting impulse to said impression cylinder or D-roll, co-operating members carried by said plate cylinder and said impression cylinder or D-roll, whereby an intermittent, unidirectional rotary movement is imparted to said impression cylinder or D-roll, and said impression cylinder or 90 D-roll is brought to rest after each rotation thereof, controlling means whereby said means for imparting the starting impulse to 95 said impression cylinder or D-roll and said co-operating members may be made inoperative and means holding said D-roll against rotation while said co-operating members are 100 in operation.

10. A printing machine embodying therein a continuously driven, rotary plate cylinder, a rotary impression cylinder or D-roll, means carried by said plate cylinder and adapted to impart a starting impulse to said 105 impression cylinder or D-roll, co-operating members carried by said plate cylinder and said impression cylinder or D-roll, whereby an intermittent, unidirectional rotary movement is imparted to said impression cylinder or D-roll, and said impression cylinder or 110 D-roll is brought to rest after each rotation thereof, controlling means whereby said means for imparting the starting impulse to said impression cylinder or D-roll and said 115 co-operating members may be made inoperative, and means whereby the actuation of said last named means is prevented while said impression cylinder or D-roll is in frictional engagement with a plate upon said 120 plate cylinder.

11. A printing machine embodying therein a continuously driven, rotary plate cylinder, a rotary impression cylinder or D-roll, means carried by said plate cylinder and 125 adapted to impart a starting impulse to said impression cylinder or D-roll, co-operating members carried by said plate cylinder and

said impression cylinder or D-roll, whereby an intermittent, unidirectional rotary movement is imparted to said impression cylinder or D-roll, and said impression cylinder or 5 D-roll is brought to rest after each rotation thereof, controlling means whereby said means for imparting the starting impulse to said impression cylinder or D-roll and said coöperating members may be made inoperative, and means whereby the actuation of 10 said last named means is prevented while said impression cylinder or D-roll is in frictional engagement with a plate upon said plate cylinder, embodying therein means operative when said coöperating members are in a neutral position, for positively shifting said coöperating members into the operative or inoperative relation.

12. A printing machine embodying there- 20 in a rotary plate cylinder, a rotary im- pression cylinder or D-roll, a segmental gear carried thereby and movable therewith, ac- tuating means for said plate cylinder, a seg- 25 mental rack slidably mounted with relation to said actuating means and adapted to mesh with said segmental gear, means acting to normally maintain said rack in a definite position, a fixed segmental guide carried by 30 said actuating means adjacent the end of said rack, means carried by said segmental gear adapted to coöperate with said guide, whereby rotation of said impression cylinder or D-roll is arrested and a slight dwell is afforded after each actuation thereof, and 35 coöperating means carried by said actuating means and said segmental gear whereby a starting impulse is imparted to said im- pression cylinder or D-roll.

13. A printing machine embodying there- 40 in a rotary plate cylinder, a rotary im- pression cylinder or D-roll, a segmental gear carried thereby and movable therewith, ac- tuating means for said plate cylinder, a seg- 45 mental rack slidably mounted with relation to said actuating means and adapted to mesh with said segmental gear, a restoring spring 50 acting on said rack, a fixed segmental guide carried by said actuating means adjacent the end of said rack, means carried by said seg- 55 mental gear adapted to coöperate with said guide, whereby rotation of said impression cylinder or D-roll is arrested and a slight dwell is afforded after each actuation thereof, coöperating means carried by said actu- 60 ating means and said segmental gear whereby a starting impulse is imparted to said impression cylinder or D-roll, and means whereby said means for imparting a starting impulse may be shifted into a relative in- operative position.

14. A printing machine embodying there- 65 in a rotary plate cylinder, a rotary im- pression cylinder or D-roll, a segmental gear carried thereby and movable therewith, ac-

tuating means for said plate cylinder, a seg- 65 mental rack slidably mounted with relation to said actuating means and adapted to mesh with said segmental gear, means acting to normally maintain said rack in a definite 70 position, a fixed segmental guide carried by said actuating means adjacent the end of said rack, a circular guide carried by said actuating means at one side of said rack, means carried by said segmental gear adapt- 75 ed to coöperate with said segmental guide or said circular guide, whereby rotation of said impression cylinder or D-roll is arrested and a slight dwell is afforded after each actuation thereof, or rotation of said D-roll may be prevented, coöperating means car- 80 ried by said actuating means and said segmental gear whereby a starting impulse may be imparted to said impression cylinder or D-roll, and means whereby said segmental gear may be shifted to make said starting 85 means inoperative and prevent the meshing of said gear with said rack.

15. A printing machine embodying there- 90 in a rotary plate cylinder, a rotary im- pression cylinder or D-roll, a segmental gear carried thereby and movable therewith, ac- 95 tuating means for said plate cylinder, a seg- mental rack slidably mounted with relation to said actuating means and adapted to mesh with said segmental gear, means acting to normally maintain said rack in a definite position, a fixed segmental guide carried by 100 said actuating means adjacent the end of said rack, removable means connecting said guide with said actuating means whereby said guide may be replaced in case of wear, means carried by said segmental gear adapted to coöperate with said guide, whereby rotation of said impression cylinder or D-roll is arrested and a slight dwell 105 is afforded after each actuation thereof, and coöperating means carried by said actuating means and said segmental gear whereby a starting impulse is imparted to said impression cylinder or D-roll. 110

16. A printing machine embodying there- 115 in a rotary plate cylinder, a rotary im- pression cylinder or D-roll, a segmental gear carried thereby and movable therewith, ac- 120 tuating means for said plate cylinder, a seg- mental rack slidably mounted with relation to said actuating means and adapted to mesh with said segmental gear, means acting to normally maintain said rack in a definite position, a fixed segmental guide 125 carried by said actuating means adjacent the end of said rack, a shoe carried by, and adjustably mounted with relation to, said segmental gear, and adapted to coöperate with said guide, whereby rotation of said impression cylinder or D-roll is arrested and a slight dwell is afforded after each actuation thereof, and coöperating means car-

- ried by said actuating means and said segmental gear whereby a starting impulse is imparted to said impression cylinder or D-roll.
17. A printing machine embodying therein a rotary plate cylinder, a rotary impression cylinder or D-roll, a segmental gear carried thereby and movable therewith, actuating means for said plate cylinder, a segmental rack slidably mounted with relation to said actuating means and adapted to mesh with said segmental gear, means acting to normally maintain said rack in a definite position, a fixed segmental guide carried by said actuating means adjacent the end of said rack, a shoe carried by, and adjustably mounted with relation to, said segmental gear, and adapted to coöperate with said guide, whereby rotation of said impression cylinder or D-roll is arrested and a slight dwell is afforded after each actuation thereof, removable means securing said shoe in relation with said gear, whereby it may be replaced in case of wear, and co-operating means carried by said actuating means and said segmental gear whereby a starting impulse is imparted to said impression cylinder or D-roll.
18. A printing machine embodying therein a rotary plate cylinder, a rotary impression cylinder or D-roll, a segmental gear carried thereby and movable therewith, actuating means for said plate cylinder, a plurality of segmental racks, slidably mounted with relation to said actuating means, and adapted respectively to mesh with said segmental gear, means acting upon said racks respectively to normally maintain each in a definite position, a plurality of fixed segmental guides carried by said actuating means intermediate said racks, means carried by said segmental gear adapted to co-operate with said guides successively, whereby rotation of said impression cylinder or D-roll is arrested and a slight dwell is afforded after each actuation thereof, a projecting arm carried by said segmental gear, and a plurality of contact studs carried by said actuating means whereby a plurality of starting impulses are imparted to said impression cylinder or D-roll with each full rotation of said actuating means.
19. A printing machine embodying therein a rotary plate cylinder, a rotary impression cylinder or D-roll, a segmental gear carried thereby and movable therewith, actuating means for said plate cylinder, a plurality of segmental racks, slidably mounted with relation to said actuating means, and adapted respectively to mesh with said segmental gear, means acting upon said racks respectively to normally maintain each in a definite position, a plurality of fixed segmental guides carried by
- said actuating means intermediate said racks, means carried by said segmental gear adapted to coöperate with said guides successively, whereby rotation of said impression cylinder or D-roll is arrested and a slight dwell is afforded after each actuation thereof, a projecting arm carried by said segmental gear, a plurality of contact studs carried by said actuating means whereby a plurality of starting impulses are imparted to said impression cylinder or D-roll with each full rotation of said actuating means, a continuous guide carried by said actuating means at one side of said racks and said segmental guides, and means for laterally shifting said segmental gear and its arm, whereby said arm is thrown out of the operative range of said studs and said means carried by said segmental gear are thrown into engagement with said continuous guide.
20. A printing machine embodying therein a rotary plate cylinder, a rotary impression cylinder or D-roll, coöperating means carried by said plate cylinder and said impression cylinder or D-roll whereby intermittent, rotary movement is imparted to the latter, means whereby said impression cylinder or D-roll may be shifted laterally to make said actuating means inoperative and prevent rotation of said impression cylinder or D-roll, and interlocking means whereby movement of said D-roll is prevented while in engagement with a plate, comprising a rotary cam having an extension or riser thereon, and an oscillatory lever, one arm of which is adapted to engage and be actuated from said impression cylinder or D-roll, and the other arm of which is provided with a contact adapted to be projected upon either side of said extension or riser.
21. A printing machine embodying therein a rotary plate cylinder, a rotary impression cylinder or D-roll, coöperating means carried by said plate cylinder and said impression cylinder or D-roll whereby intermittent, rotary movement is imparted to the latter, means whereby said impression cylinder or D-roll may be shifted laterally to make said actuating means inoperative and prevent the rotation of said impression cylinder or D-roll, and interlocking means whereby movement of said D-roll is prevented while in engagement with a plate, comprising a rotary cam having an extension or riser thereon, and an oscillatory lever, one arm of which is adapted to engage and be actuated from said impression cylinder or D-roll, and the other arm of which is provided with a contact adapted to be projected upon either side of said extension or riser, the forward edge of said extension or riser being brought to a

point and said contact being graduated toward its edges whereby in case of said actuating means being in a neutral position, said extension or riser will positively and 5 mechanically complete the movement thereof.

In witness whereof, I have hereunto

affixed my signature, in the presence of two subscribing witnesses, this 28th day of June, 1913.

FRANK C. MARQUARDT.
